(57) **CLAIM**

The ornamental design for a packaging container, as shown and described.

DESCRIPTION

FIG. 1 is a front perspective view of the first embodiment of a packaging container showing my new design;

FIG. 2 is a rear perspective view of FIG. 1;
FIG. 3 is a front elevational view of FIG. 1;
FIG. 4 is a rear elevational view of FIG. 1;
FIG. 5 is a right side elevational view of FIG. 1; the left side elevational view of FIG. 1 is a mirror image of the right side elevational view of FIG. 1;
FIG. 6 is a top plan view of FIG. 1; the bottom plan view of FIG. 1 is a mirror image of the top plan view of FIG. 1;
FIG. 7 is a front perspective view of the lid and case of the packaging container in FIG. 1;
FIG. 8 is a rear perspective view of FIG. 7;
FIG. 9 is a front elevational view of FIG. 7;
FIG. 10 is a rear elevational view of FIG. 7;
FIG. 11 is a right side elevational view of FIG. 7; the left side elevational view of FIG. 7 is a mirror image of the right side elevational view of FIG. 7;
FIG. 12 is a top plan view of FIG. 7; the bottom plan view of FIG. 7 is a mirror image of the top plan view of FIG. 7;
FIG. 13 is a front perspective view of the lid of the packaging container of FIG. 1;
FIG. 14 is a rear perspective view of FIG. 13;
FIG. 15 is a right side elevational view of FIG. 13; the left side elevational view of FIG. 13 is a mirror image of the right side elevational view of FIG. 13;
FIG. 16 is a top plan view of FIG. 13; the bottom plan view of FIG. 13 is a mirror image of the top plan view of FIG. 13;
FIG. 17 is a front perspective view of the case of the packaging container in FIG. 1;
FIG. 18 is a rear perspective view of FIG. 17;
FIG. 19 is a front elevational view of FIG. 17;
FIG. 20 is a rear elevational view of FIG. 17;
FIG. 21 is a right side elevational view of FIG. 17; the left side elevational view of FIG. 17 is a mirror image of the right side elevational view of FIG. 17;
FIG. 22 is a top plan view of FIG. 17; the bottom plan view of FIG. 17 is a mirror image of the top plan view of FIG. 17;
FIG. 23 is a front perspective view of the second embodiment of a packaging container showing my new design;
FIG. 24 is a rear perspective view of FIG. 23;
FIG. 25 is a front elevational view of FIG. 23;
FIG. 26 is a rear elevational view of FIG. 23;
(Continued)

FIG. 27 is a right side elevational view of FIG. 23; the left side elevational view of FIG. 23 is a mirror image of the right side elevational view of FIG. 23;
 FIG. 28 is a top plan view of FIG. 23; the bottom plan view of FIG. 23 is a mirror image of the top plan view of FIG. 23;
 FIG. 29 is a front perspective view of the lid and case of the packaging container in FIG. 23;
 FIG. 30 is a rear perspective view of FIG. 29;
 FIG. 31 is a front view of FIG. 29;
 FIG. 32 is a rear view of FIG. 29;
 FIG. 33 is a right side elevational view of FIG. 29; the left side elevational view of FIG. 29 is a mirror image of the right side elevational view of FIG. 29;
 FIG. 34 is a top plan view of FIG. 29; the bottom plan view of FIG. 29 is a mirror image of the top plan view of FIG. 29;
 FIG. 35 is a front perspective view of the lid of the packaging container of FIG. 23;
 FIG. 36 is a rear perspective view of FIG. 35;
 FIG. 37 is a right side elevational view of FIG. 35; the left side elevational view of FIG. 35 is a mirror image of the right side elevational view of FIG. 35;
 FIG. 38 is a top plan view of FIG. 35; the bottom plan view of FIG. 35 is a mirror image of the top plan view of FIG. 35;
 FIG. 39 is a front perspective view of the case of the packaging container in FIG. 23;
 FIG. 40 is a rear perspective view of FIG. 39;
 FIG. 41 is a front elevational view of FIG. 39;
 FIG. 42 is a rear elevational view of FIG. 39;
 FIG. 43 is a right side elevational view of FIG. 39; the left side elevational view of FIG. 39 is a mirror image of the right side elevational view of FIG. 39; and,
 FIG. 44 is a top plan view of FIG. 39; the bottom plan view of FIG. 39 is a mirror image of the top plan view of FIG. 39.

In the drawings, the broken lines are for the purpose of illustrating portions of the packaging container which form no part of the claimed design.
